ROTARY VALVE FOR GAS-ENGINES.

SPECIFICATION forming part of Letters Patent No. 727,917, dated May 12, 1903.

Application filed October 5, 1900. Serial No. 32,065. (No model.)

To all whom it may concern:

Be it known that I, SILAS H. DYER, a citizen of the United States, residing at Pawtucket, in the county of Providence and State of Rhode Island, have invented a new and useful Improvement in Rotary Valves for Gas-Engines, of which the following is a specification.

This invention has reference to an improvement in valves for gas-engines whereby at predetermined intervals the supply of the explosive mixture and the exhaust are controlled; and it consists in the peculiar and novel construction and the combination of the parts whereby the valve is protected against the blow exerted by the explosion, as will be more fully set forth hereinafter.

Figure 1 is a side view of the end of the cylinder and the valve-chamber. Fig. 2 is a vertical sectional view through the center of Fig. 1. Fig. 3 is a vertical sectional view, taken at right angle to Fig. 2, on the line X-X of Fig. 1. Fig. 4 is a horizontal sectional view on the line Y-Y of Fig. 1.

Similar letters of reference indicate corresponding parts in all the figures.

In the drawings, *a* indicates the cylinder, and *a'* the piston, of the engine; *b*, a cylindrical valve-chamber supported on a circular flange *b'*, by which it is secured to the end of the cylinder. The central opening *b*² connects the interior of the valve-chamber with the interior of the cylinder. The valve-chamber *b* has at one side the removable cover *b*³. The inlet and exhaust ducts are formed in the transverse enlargement *b*⁴ of the cover *b*³. In the cover *b*³ the post *b*⁵ is adjustably secured by means of a set-screw, and on the inner end of the post the disk *b*⁶ is secured.

The valve *c* is rotatably supported on the post *b*⁵ and is in frictional contact at one end with the inner surface of the cover and at the other end with the disk *b*⁶. The valve is provided with a duct the inlet *c*' of which registers in the rotation of the valve with the ports of the inlet and outlet ducts, terminating in the inner surface of the cover. The outlet *c*² of the duct is in the peripheral surface of the valve and communicates with the annular space *c*³ between the valve *c* and the inner surface of the valve-chamber *b*. The valve

c is rotated by the shaft *d*, journaled in the valve-chamber. The arm *d'* is secured to the shaft *d* and carries the pins *d*² *d*³, which engage with the lugs on the valve *c*.

When in use, the parts exposed to the heat of the successive explosions become heated and expand. By the use of the adjustable post *b*⁵ the disk *b*⁶ may be adjusted to the valve and secure the close contact of the ends *b*⁶ of the valve *c* with the disk *b*⁶ and with the inner surface of the cover *b*³ in the working condition without binding. When the inlet-duct *b*⁷ is connected with the pipe supplying the explosive mixture and the opening *c*' of the duct in the valve registers with the port of the duct *b*⁷, the explosive mixture may pass into the valve-chamber and into the cylinder, and after the explosion when the duct in the valve registers with the outlet-duct *b*⁸, as is shown in Fig. 4, the products of combustion may be discharged through the outlet-duct. The force of the explosion is exerted only on the peripheral surface of the valve and not on the ends, the pounding of the valve is avoided, and the wear reduced, thereby preventing leaking and repairs.

Having thus described my invention, I claim as new and desire to secure by Letters Patent—

1. In a gas-engine, the combination with the cylinder, a cylindrical valve-chamber having a tangential flange and an opening through the same connecting the interiors of the valve-chamber and the cylinder, and inlet and outlet ducts in the valve-chamber, of a cylindrical valve-body of less diameter than the interior of the valve-chamber, a post projecting centrally into the valve-chamber and forming the journal-support of the valve, a disk or head covering the outer face of the valve and secured to the journal-support of the valve, a duct extending from one end of said valve through the body thereof to the peripheral surface of the valve-body, and means for rotating the valve, as described.

2. In combination with the end of the cylinder *a*, the valve-chamber *b*, and the inlet and outlet ducts of a gas-engine, of the valve-body *c*, the duct in the valve-body having the inlet *c*' in the end and the outlet *c*² in the peripheral surface of the valve, the adjustable

post b^5 , the disk b^6 on the inner end of said post, and means for rotating the valve, as described.

3. In a gas-engine, the combination with 5 the cylinder, and the valve-chamber the interior of which communicates with the interior of the cylinder, of the removable cover b^3 , the inlet-duct b^7 and outlet-duct b^8 in the cover, the post b^5 adjustably secured in the 10 cover, the disk b^6 on the post, the valve-body c rotatably supported on the post b^5 between the cover and the disk b^6 , the duct in the

valve registering with the inlet and outlet ducts, the shaft d , the arm d' , and the pins d^2 d^2 connecting with and rotating the valve- 15 body, as described.

In testimony whereof I have signed my name to this specification in the presence of two subscribing witnesses.

S. H. DYER
